INVENTOR.

James E. Jackson
By his Attorney,
Nelson M. Howard

UNITED STATES PATENT OFFICE.

JAMES E. JACKSON, OF LYNN, MASSACHUSETTS, ASSIGNOR TO UNITED SHOE MANUFACTURING CORPORATION, OF PATERSON, NEW JERSEY, A CORPORATION OF NEW JERSEY.

CHANNEL-OPENING MACHINE.

1,407,037.

Specification of Letters Patent. Patented Feb. 21, 1922.

Application filed April 5, 1920. Serial No. 371,310.

To all whom it may concern:

Be it known that I, JAMES E. JACKSON, a citizen of the United States, residing at Lynn, in the county of Essex and State of Massachusetts, have invented certain Improvements in Channel-Opening Machines, of which the following description, in connection with the accompanying drawings, is a specification, like reference characters on the drawings indicating like parts in the several figures.

This invention relates to channel opening machines, and more particularly to machines for turning lips of soles prior to their attachment to boots or shoes.

It is common in the manufacture of McKay shoes to use channel opening or lip turning machines by which the channel lip is turned over by a wiper rotating in a horizontal plane and is pressed down upon the sole by a stationary presser foot arranged at the rear of the wiper. The sole is advanced against these lip turning devices by a feed wheel upon the toothed edge of which it is supported at its margin, the feed wheel being yieldingly pressed upwardly toward said devices.

It is an object of the present invention to provide improved work feeding means applicable to such machines, and of such a character as to adapt the machines to operate more effectively upon outsoles to which a metal shank stiffener has previously been attached. Such soles cannot advantageously be handled by the machines heretofore used for this purpose, since the metal shank stiffener interferes with the feed wheel of the machine.

A feature of the invention lies in the provision in such a machine, of a work feeding wheel having a work engaging edge so narrow as to pass between the metal shank stiffener and the edge of the sole to be operated upon, the feed wheel preferably being also provided with a portion concave in radial section so as to avoid damage or excessive friction when, as occasionally happens, the unsupported part of the body of the sole operated upon is displaced downwardly somewhat, the edge of the concave portion remote from the work feeding edge nevertheless positively limiting such downward displacement.

A further feature of the invention lies in

the provision of a work support adjacent to the feed wheel of such a machine, the work support being arranged with its work engaging portion extending in the direction of the width of the sole operated upon, that is, at right angles to the plane of rotation of the feed wheel, so as to prevent undesired downward displacement of the edge of the sole. This work support may advantageously be arranged for movement with the feed wheel towards and from the work.

Other features of the invention will be hereafter described, and pointed out in the appended claims.

In the accompanying drawings,

Fig. 1 is a side elevation with certain parts broken away and in section showing the invention as applied to a channel opening machine of the type disclosed in U. S. Letters Patent No. 1,030,630, granted on an application filed June 25, 1912 in the name of Henry W. Winter; and

Fig. 2 is a perspective view with parts broken away and in section of the work feeding and channel opening portions of the machine.

The machine as shown is provided with a wiper 10 carried by a shaft 12 and rotated in the direction of the arrow in Fig. 1. This wiper is formed to bend over and press down the channel flap to be operated upon. Co-operating with the wiper and acting subsequently thereto to press the lip closely into engagement with the sole is a stationary presser foot 14. A channel gage 16 is provided to enter the channel and limit the extent to which a sole may be inserted beneath the wiper 10. It will be understood that the wiper, presser foot and the channel gage are well known in the art and a further detailed description thereof is for that reason not herein given.

A feed wheel for presenting the work to the channel opening means is indicated generally at 20. This wheel is mounted upon a shaft 22 which is somewhat inclined with respect to the operative plane of the wiper and is journaled in a suitable bearing in a sliding block 24 movable in a vertical guide-way 28 and sustained therein against downward movement by a spring 30. The sliding block 24 is provided with a forward extension 32 to which is attached a rod 34. Through tension exerted on this rod the

sliding block may be moved downward against the action of spring 30 so as to lower the feed wheel from the wiper for the convenient insertion of the work at the commencement of a channel opening operation.

The feed wheel 20, as shown, consists of a hollow hub 36 provided with a flange 38, the latter supporting a peripherally toothed disk 40 of a somewhat greater diameter than the flange 38. Arranged adjacent to the disk 40 on the side thereof remote from the flange 38, is a member 42 having a portion thereof adjacent the disk 40 concave in radial section, as indicated at 44, and having the portion remote from the disk 40 in the form of a cone of but little inclination and approximating to a cylinder as shown at 46. These parts of the feed wheel are keyed to the hollow hub 36 as indicated at 48 and are clamped thereto by a hub 50 provided with a flange 52 overlying the member 42 and provided with a screw 54 threaded into shaft 22. Co-operating with the feed wheel to properly present the work to the wiper and presser foot, is a work support 56 having a work engaging portion, as indicated in Fig. 2, concentric with the feed wheel and carried by the extension 32 of the slide block 24 for movement towards and from the wiper with the feed wheel. This work support is so arranged that a cross section thereof taken through the axes of rotation of the wiper and of the feed wheel is parallel to the axis of rotation of the feed wheel and, accordingly, the work support lies at that inclination to the operative plane of the wiper which the sole operated upon naturally tends to assume.

Co-operating with the feed wheel 20 and the work support 56 is an edge gage shown as a conical roll 58 idly engaging the edge of the work and adjustably mounted with respect thereto, as by a slide 60 carried by a slideway 62 and clamped therein by a screw 64. As is apparent from Fig. 1, the work engaging element of this cone is at right angles to the axis of rotation of the feed wheel 20, the work support 56 and the edge gage 58 being so arranged as effectively to support the edge of a sole to be operated upon even though that edge be quite thin as, for instance, if it is beveled, and to prevent downward turning thereof or any other damage thereto. It should also be observed that the peripherally toothed disk 40 is of such a width that a sole having a metal shank attached thereto may be fed to the channel opening elements without interference by the metal shank. Moreover, if, as sometimes happens, the outer portion of the sole be displaced downwardly the metal shank will come into contact only with the portion 46 of the feed wheel which is so formed as neither to damage or be damaged by the metal shank but positively to limit the extent

of such downward displacement and this without interference with the effective operation of the machine.

In the operation of the machine the wiper 10 and the feed wheel 20 are continuously rotated. The feed wheel is displaced by tension exerted on the rod 34 to permit the insertion of a sole. The sole to be operated upon is placed in the machine so that the channel gage 16 lies in the channel beneath the channel lip and with its marginal portion supported by the work support 56 and its edge in contact with the roll 58. As the sole is advanced against the rotary wiper and the presser foot the wiper exerts a rubbing action on the edge of the channel lip, raises it, and bends it over and down upon the sole, the presser foot acting subsequently in the usual manner. When the sole operated upon is provided with a metal shank, the teeth 40 of the feed wheel will pass adjacent to the edge of the shank but without contact therewith and at all times the edge of the sole is effectively supported and protected from damage, as previously described. Since the work support is carried by the guide block 24 which also carries the feed wheel any movement of the latter towards or from the wiper will result in a similar movement of the work support so that the edge portion of the sole is at all times supported in the same manner and since this movement is at right angles to the operative plane of the wiper, the sole will at all times be presented thereto at the same inclination irrespective of the actual position of the feed wheel.

In the accompanying claims, the term "cone" as applied to the part 46, is intended to be taken in a sense broad enough to include a cylinder which, of course, is the limiting form of a cone.

Having described my invention, what I claim as new and desire to secure by Letters Patent of the United States is:

1. A machine for turning the channel lips of soles having, in combination, a rotary wiper, a feed wheel having its axis inclined with respect to the operative plane of said wiper, an edge gage consisting of a roll with its work engaging element at right angles to the axis of rotation of said feed wheel, and a work support provided with a work engaging surface between the feed wheel and the edge gage and perpendicular to the plane of the latter.

2. A machine for turning the channel lips of soles having, in combination, a wiper, a feed wheel having its axis inclined with respect to the operative plane of the wiper, an arcuate work support arranged perpendicular to the plane of rotation of the feed wheel and adjacent thereto, and means for guiding said feed wheel and work support for movement towards and from said wiper

in a path perpendicular to the operative plane thereof.

3. A machine for turning the channel lips of soles having, in combination, a wiper, a feed wheel having its axis inclined with respect to the operative plane of said wiper, a work support adjacent to the work engaging portion of said feed wheel and perpendicular to the plane of rotation thereof, 10 and means to guide said feed wheel and work support for movement towards and from said wiper in a path perpendicular to the operative plane thereof.

4. A machine for turning the channel lips 15 of soles having, in combination, a wiper, a feed wheel having its axis inclined with respect to the operative plane of said wiper, and a work support having a work engaging surface at right angles to the plane of rotation of said feed wheel.

5. A machine for turning the channel lips of soles having, in combination, a feed wheel having a work engaging edge and an outside edge spaced therefrom and of a lesser 25 diameter for limiting downward displacement of a sole supported by the work engaging edge, and an arcuate work support arranged adjacent to said feed wheel below the edge thereof and at right angles to the 30 plane of rotation thereof.

6. A machine for turning the channel lips of soles having, in combination, a rotary 35 wiper and a feed wheel having a narrow edge to engage the lower surface of a sole and a second narrow edge of lesser diameter adjacent thereto on the side remote from the

edge of the work to be operated upon, for limiting downward displacement of the work.

7. A machine for turning the channel lips 40 of soles having, in combination, a wiper arranged for rotation about a substantially vertical axis and a feed wheel having a narrow edge to engage the lower side of the work and having a second narrow edge of 45 lesser diameter adjacent thereto on the side remote from the edge of the work to be operated upon for limiting downward displacement of the work, said feed wheel being arranged for rotation about an axis inclined 50 with respect to the operative plane of said wiper.

8. In a machine of the class described, a feed wheel having a narrow work engaging edge, a conical portion of less diameter than 55 that of said work engaging edge, and a cut-out portion between said conical portion and said work engaging edge, by which construction the work-engaging edge will support the work while the conical portion will limit 60 downward displacement of the work.

9. A machine of the class described comprising a feed wheel having a toothed edge to engage and support the lower side of the work, a conical portion removed therefrom 65 to limit downward displacement of the work, and a cut-out portion between said conical portion and said toothed edge to avoid engaging the work.

In testimony whereof I have signed my 70 name to this specification.

JAMES E. JACKSON.
